UNITED STATES PATENT OFFICE.

FRANCIS M. RITES, OF SLATERVILLE SPRINGS, NEW YORK; CHARLES H. GALLAGHER, EXECUTOR OF SAID RITES, DECEASED, ASSIGNOR TO PERIE CLAPP RITES, OF ITHACA, NEW YORK, GUARDIAN OF MARION B. RITES.

INTERNAL-COMBUSTION ENGINE.

1,178,181.

Specification of Letters Patent.

Patented Apr. 4, 1916.

Application filed January 17, 1913. Serial No. 742,720.

To all whom it may concern:

Be it known that I, FRANCIS M. RITES, a citizen of the United States, residing at Slaterville Springs, in the county of Tompkins and State of New York, have invented certain new and useful Improvements in Internal-Combustion Engines, of which the following is a specification.

The object of my invention is to produce a simplified form of internal combustion engine particularly suitable for fuel, normally liquid; together with novel means for carbureting, vaporizing, atomizing and igniting said fuel.

Another object of my invention is to construct the engine so that it will by novel means furnish a continuous supply of compressed air during its operation.

Another object of my invention is to store the compressed air so furnished by the operation and use it for mixing with the hydrocarbon to furnish a combustible mixture at a high initial pressure.

These and other objects of my invention will be fully illustrated in the drawings, described in the specification and pointed out in the claim at the end thereof.

In the accompanying drawings, Figure 1 is a longitudinal vertical section of my improved engine taken on the line 1^x—1^x in Fig. 3. Fig. 2 is a top plan view of my improved engine. Fig. 3 is a vertical transverse section taken on the line 3^x—3^x of Fig. 1. Fig. 4 is an end elevation of my improved engine, 35 showing the valve operating mechanism. Fig. 5 is a horizontal section on the line 5^x—5^x in Fig. 3. Fig. 6 is a horizontal section on the line 6^x—6^x in Fig. 3.

In the accompanying drawings like reference numerals indicate like parts.

In the drawings reference numeral 1 indicates an engine which is provided with a crank case 2 and the cylinder casings 3 and 4. In the crank case is mounted to rotate the 45 crank shaft 5 having four cranks therein, one for each of the cylinders of the engine, these cranks being placed ninety degrees apart from each other; as is indicated diagrammatically in Fig. 3. On each of the 50 cranks is provided the connecting rod 6, which connecting rod is connected to the crank at one end and to the trunk piston at the other end. Each of these trunk pistons

is composed of a long plunger 7 of small diameter and a short plunger 8 of large 55 diameter. Each of these plungers operates in a cylinder of corresponding diameter, with which the plungers are adapted to make a steam or gas tight fit by means of packing rings. The plunger 7 operates in 60 the cylinder 9 and the plunger 8 operates in the cylinder 10. On the downward stroke of each of the pistons the plunger 8 operates to compress the air entrapped in the cylinder 10 below the plunger. For this purpose each 65 of the cylinders 10 is provided at its lower edge with an admission valve 11 on one side and an exhaust valve 12 on the other side, it being understood that when the plunger 8 is on the upward stroke it will draw in air 70 from the surrounding atmosphere through the admission valve, the valve 11 being lifted by the suction, and on the downward stroke the plunger 8 will compress the air so entrapped, closing the valve 11 and opening 75 the valve 12 by the pressure, causing the air so compressed to flow through the exhaust valve 12 into the storage cylinder 13. Any of the ordinary forms of valves may be used for the admission and exhaust valves 80 11 and 12.

From the compressed air reservoir 13 a tube or pipe leads upward to each of the engine cylinders for the purpose of conveying the compressed air to the admission 85 valve of each cylinder. Such pipe is indicated at 14 in Fig. 3. The pipe 14 connects with the air chamber 15 in which is mounted to operate the admission valve 16. This admission valve has the hollow stem 90 17 integral therewith, which stem passes through the cover plate 18 for the air chamber, making an air tight joint therewith. The stem 17 carries the collar 19 on top thereof, with which collar the lever 20 engages for the purpose of lifting it. This lever is mounted to rock upon the pin 21 and has connected thereto at its opposite end the link 22, which link is connected to the crank 23 on the rock shaft 24. The rock 100 shaft 24 has on the end thereof the crank 25 to which is connected the eccentric rod 26, which in turn is reciprocated by the eccentric or cam 27. Similar valve operating mechanism is placed upon the opposite side 105 of the engine.

Upon the shaft 24 is also placed a second crank 28 which is connected by similar gear to the admission valve of the next adjacent cylinder, the crank being placed or timed so that it will operate the admission valve at the appropriate interval. The stem 17 of the admission valve is perforated to receive therein the tube 30 through which the liquid hydrocarbon may be fed to the engine. The tube 30 is stationary and is connected to the reservoir in which the liquid hydrocarbon is maintained under pressure for fuel purposes. The liquid hydrocarbon is maintained under such a pressure and temperature that when it is admitted to the cylinder or ignition chamber it will "explode" and ignite, due to the rapid expansion of its more volatile ingredients. This feature however constitutes no part of this invention, as it is disclosed and claimed in another application.

The valve 16 coöperates with the seat 31 in the cylinder head to regulate the air intake and coöperates with the seat 32 on the baffle plate 33 to regulate the hydrocarbon intake. The baffle plate 33 is illustrated in Figs. 3 and 6 and consists of a casting having two sets of openings therein. One of these openings 34 communicates on one side with the auxiliary burner 35 by which it is heated, and on the other side communicates with the exhaust opening 36 by which the products of combustion from the auxiliary burner 35 are carried away. The auxiliary burner consists of any convenient form of torch by which heat can be generated and applied to the interior of the baffle plate. Independent of the opening 34 are the openings 37 and 38 by which an explosive or combustible charge is admitted from the valve to the engine cylinder, the various discharges being arranged to secure the maximum heating and dissipating effect on the charge from the baffle plate.

The engine is operated preferably as a two-cycle engine. The valves are so timed as to admit the explosive or combustible charge to the cylinder when the piston is at the beginning of the stroke, the valve remaining open and continuing to admit a charge as long as may be desired. It will be understood that the charge is admitted with an initial pressure which is as high as may be desired, and the combustion or explosion of the charge begins as soon as a fresh charge comes into contact with or passes the baffle plate, but is not completed until a perceptible interval of time has elapsed, due to the slow burning quality or the slow explosive quality of the charge that is taken in, which charge is made up of all the elements of the crude oil instead of merely the more volatile or more explosive or the more rapid burning elements of the crude oil. For this reason the valve gear is so arranged as to

cause the admission valve to remain open for a predetermined time during the forward stroke of the piston.

It will be understood that as the combustible mixture burns in the cylinder the product of combustion occupies a much larger volume than did the original product. This in turn affects the quantity of the combustible mixture that must be admitted to the cylinder in order to fill the cylinder and clearance up to the point of cut off. After the cut off takes place the products of combustion expand driving the piston forward and giving an indicator card which is more like that of a steam engine than of the familiar card of the gas engine. It will also be understood that when the cut off takes place the combustion in the cylinder may not be completed, but can continue during the forward stroke of the piston until it is completed, causing still further increase in the volume of gases in the cylinder, with corresponding increase in power or a larger area of the card, according to the grade or kind of fuel used.

When the piston has completed its forward stroke the continued rotation of the crank shaft carries the piston on its return stroke and during the return stroke the admission valve remains closed and the exhaust valve 40 is opened by the lever 41 mounted upon the pin 42, and operated by the link 43 from the crank 44 which in turn is mounted on the shaft 45 and operated by the crank 46 from the eccentric rod 47, which in turn is driven by the eccentric or cam 48 mounted on the crank shaft 5. The exhaust valve 40 communicates with the exhaust pipe 50 by which the burned gases of the engine are conveyed away.

The operation of my improved engine is as follows: The torch or burner 35 is ignited for the purpose of heating the baffle plate 33. When the baffle plate has been sufficiently heated the engine is started. The upward stroke of each of the pistons sucks in a charge of air thereunder and the downward stroke of the piston compresses this air and discharges it into the storage cylinder 13. This air in turn is admitted to the cylinder by means of the admission valve 16, which valve is raised by the valve gear heretofore described and which valve also controls the admission of the fluid hydrocarbon. Both the air and the hydrocarbon are thrown into contact with the heated baffle plate and pass into the cylinder, combustion therein having already been begun. The forward stroke of the piston has in the meantime been begun and the combustion of the charge causes an expansion of the charge, filling the cylinder and driving the piston before it. This expansion continues during the forward stroke of the piston and is added to as long as the admission valve remains

open. The admission valve closes at a pre-determined point and when the piston reaches the end of its stroke the exhaust valve is open and the exhaust then takes 5 place during the forward stroke of the piston.

It will be understood that the admission valve may be left open a longer or shorter time during the forward stroke of the piston 10 ton, according as it is desired to operate the engine at a higher or lower pressure of admission and higher or lower efficiency, and according to the design of the engine.

It will also be understood that with a short 15 cut off the pressure of admission will be high and the engine must be built correspondingly stronger in order to stand the increased strain, but the engine will be correspondingly more efficient. If a long cut off is 20 used the pressure of admission will be correspondingly lower. The engine can be of lighter construction and the efficiency will be correspondingly lower.

It will also be understood that the preliminary heating of the baffle plate is necessary 25 only to start the engine. Afterward in regular operation the natural heating of continued combustion will maintain it sufficiently high in temperature and it will be 30 seen from an inspection of the drawings that the shape and location of the baffle plate is adapted to secure this result.

It will also be understood that if desired gas may be used as fuel for my engine in-

stead of oil but in either case, the gas or oil 35 must be under sufficient pressure to enable it to enter the cylinder against the pressure that is present during admission.

Having thus described my invention, what I claim as new and patentable is as follows: 40

In an internal combustion engine the combination of a casing having two cylinders of different diameters arranged therein in series, a piston made up of two plungers of different diameters arranged in series, the 45 plunger of large diameter having a large working surface on top and a reduced working surface on the bottom, said plungers being mounted to reciprocate in said cylinders, a port at one end of the large cylinder for 50 admitting a combustible mixture, means controlling the admission of said mixture, means for igniting said mixture as it enters the cylinder, inlet and exhaust valves in the large cylinder adjacent to the small cylinder regulating the flow of air into and out of the large cylinder and around the small plunger whereby said piston may be driven by the pressure on the large working surface 55 of the large plunger and caused to pump air with the reduced working surface of the 60 large plunger.

In testimony whereof I affix my signature in presence of two witnesses.
